UNITED STATES PATENT OFFICE.

JAMES S. PATES, OF MIDWAY, KENTUCKY.

BURGLAR-ALARM.

SPECIFICATION forming part of Letters Patent No. 596,379, dated December 28, 1897.

Application filed March 24, 1897. Serial No. 629,063. (No model.)

To all whom it may concern:

Be it known that I, JAMES S. PATES, residing at Midway, in the county of Woodford and State of Kentucky, have invented a new 5 and Improved Burglar-Alarm, of which the following is a specification.

My invention is in the nature of a portable burglar-alarm which can be readily adapted to a door or window in such a manner that 10 the opening of the door or window will produce an alarm.

My invention primarily has for its object 15 to provide a device of this character of a very simple and inexpensive nature which can be carried in the pocket or a small valise, which is of a very simple and economical construction, and which can be almost instantly applied at such point as may be desired.

With other objects in view, which will hereinafter be made apparent, the invention consists in a burglar-alarm embodying the peculiar combination and construction of parts such as will be first described in detail, and then be specifically pointed out in the appended claims, reference being had to the accompanying drawings, in which—

Figure 1 is a view illustrating my invention as applied for use. Fig. 2 is a view illustrating the same connected with a window. 30 Fig. 3 is a detail sectional view illustrating the clamp device as applied in a narrow space between the door and casing. Fig. 4 is a similar view illustrating the clamp set in a wide spacing between the door and casing. Fig. 5 is a detail view, on an enlarged scale, of the alarm devices. Fig. 6 is a view illustrating the detachable connection for joining the whistle with the air-tube, and Fig. 7 is a detail view of the clamp devices hereinafter referred to.

In its practical construction my invention consists of an inflatable body having an air-tube provided with a whistle or other air-operated alarm at its outer end and a clamp device adapted to be inserted in the space between the edge of the door and the casing or the window-sash and casing.

Referring now to the accompanying drawings, in which like numerals indicate like 50 parts in all the figures, 1 indicates an inflatable bag, which may be of any desired form and which has an air-tube 2, the upper end

of which is connected with an internally-threaded ring 3, having an enlarged or bulb portion 4, whereby the end of the flexible tube can be securely held thereon at a suitable point on its exterior face. The air-bag has a flexible eye 5, to which is connected the flexible band or cord 6, which forms a supporting-loop for the said bag, as the same is 60 adapted to be slipped over on the knob of a door, as shown in Fig. 1, or other fixed supporting means.

7 indicates an alarm device, which in the present instance is in the nature of a whistle 65 which has its air-inlet end terminating in an exteriorly-threaded shank 8, adapted to be screwed into the member 3, as clearly shown in Fig. 6.

9 indicates a clamp, which consists of a 70 base member 9^a, terminating in a flat sharpened end 9^b and having an eye 9^c, in which is held the pintle 10, on which is pivotally secured the hinge clamp member 11. This clamp member is formed of spring metal and 75 has its portion 11^b normally held against the base 9^a in such a manner that it will be forced out to the position shown in full lines in Fig. 7. The clamp member 11 has its inner portion made approximately parallel with 80 the base 9^a, as shown at 11^b, which portion is bent out at an angle indicated by 11^c and then bent forward, as at 11^d, and terminating in a sharpened portion, as shown.

The object in providing a clamp member 85 as shown and described is to provide for securing such clamp either in a narrow or wide slit or space between the door and casing, as shown in Figs. 3 and 4, and also to provide for a positive clamping or squeezing of the 90 tube 2 to prevent the escape of air when such clamp device is secured in a wide or narrow space. Furthermore, as the member 11 has its inner end made to engage the base 9^a, so that it will be normally forced outward, as 95 shown in full lines in Fig. 7, it follows that the closer the ends of the clamp are brought together the more tightly will it squeeze the tube 2 and close off the escape of air, such arrangement of clamp device, however, providing for a positive closing off of the tube, even when the ends thereof are at or near the position shown in full lines in Fig. 7.

In operation the bag is filled with air, which

is readily accomplished by disconnecting the whistle from the member 3, using the member 3 as a mouthpiece, and holding the clamp with the fingers about the neck of the tube, it being obvious that by arranging the parts as shown the operator can hold the clamp and the end of the tube with one hand and the clamp compressed, so as to prevent the escape of air, while using the other hand for securing the whistle to the mouthpiece 3. Having thus blown up the bag, it can be supported on the knob, as shown in Fig. 1, or upon a nail or other suitable support and the ends of the clamp shoved in between the end of the door and the casing, as shown in Fig. 1, or between the sash and the window-casing, as shown in Fig. 2.

From the foregoing description, taken in connection with the accompanying drawings, it is thought the full advantages of my invention will be readily understood. The same can be manufactured at a very small cost and will be found a very useful device for the household, and especially for travelers.

Having thus described my invention, what I claim, and desire to secure by Letters Patent, is—

1. A burglar - alarm, comprising an air-holder having a flexible escape-tube provided with a whistle or other alarm mouthpiece detachably connected therewith, and a clamp device adapted to be secured at any point on the flexible tube and having its ends adapted to be secured between the door and casing, whereby to close the said tube substantially as shown and described.

2. A new and improved burglar-alarm, comprising an air-holding bag having a flexible hanger and a tube having a mouthpiece, a whistle having a threaded shank to engage the mouthpiece, and a clamp consisting of a base member having a sharpened front end, a spring member hinged thereto in such a manner as to open normally outward from the base said clamp having a portion held in close relation to the base, an outwardly-bent portion and a forwardly-extending member held normally spaced apart from the base member all being arranged substantially as shown and for the purposes described.

JAMES S. PATES.
